INTERMITTENTLY-VARIABLE DRIVE
MECHANISM

Michael F. Campbell, Sterling, Colo.

Application September 1, 1951, Serial No. 244,820

1 Claim. (Cl. 273—86)

1

This invention is concerned with means in driven association with a single prime mover or source of power whereby a plurality of separate, like elements may be simultaneously actuated at intermittently variable speeds, and has as an object to provide an arrangement of such means wherein the speed variations affecting the actuated elements are solely a matter of hazard and entirely unpredictable.

A further object of the invention is to provide improved means for simultaneously actuating a plurality of separate, like elements at intermittently-variable speeds and in a common direction from a single power source.

A further object of the invention is to provide an improved unitary assembly of elements constituting an intermittently-variable drive mechanism for the simultaneous and non-synchronous actuation of a plurality of separate, like elements, which mechanism is compact, simple of construction and operation, positive and efficient in use, susceptible of ready adjustment for wide variation of the specific speed differentials deriving therefrom, and adaptable to operative association with a variety of specific installations and arrangements of elements to be actuated thereby.

With the foregoing and other objects in view, my invention consists in the construction, arrangement, and combination of elements as hereinafter set forth, pointed out in my claim, and illustrated by the accompanying drawings, in which—

Figure 1 is a plan view of a typical embodiment of the invention as applied to the simultaneous actuation of four separate, like elements at unpredictably and intermittently variable speeds. Figure 2 is a section longitudinally of the arrangement according to Figure 1, on an enlarged scale and with certain portions broken away to conserve space and to disclose otherwise concealed construction, taken substantially on the indicated line 2—2 of Figure 1. Figure 3 is a fragmentary, detail elevation, on a further enlarged scale, of the rearward end of the typical unit assembly shown in Figure 2. Figure 4 is a fragmentary, detail section taken substantially on the indicated line 4—4 of Figure 3. Figure 5 is a fragmentary, plan view, on a relatively enlarged scale, of the forward, or driving, end of the assembly according to Figure 1. Figure 6 is a side elevation of the showing of Figure 5 as viewed from the zone indicated by the line 6—6 of said latter figure. Figure 7 is a fragmentary, detail section, on a relatively enlarged scale, taken substantially on the indicated line 7—7 of Figure 5.

2

The improved drive mechanism illustrated by the drawings and hereinafter described is primarily designed for operative association with a plurality of identical toy elements, such as horses, dogs, automobiles, and the like, which are suitably arranged on and for independent travel along or about a board or field simulating a race course, so that the actuation of said elements deriving from the improved mechanism is productive of a variation in the relative speeds of the actuated elements in a manner closely simulating a race or speed contest. Means analogous as to result are common and well known, but the particular distinctive characteristic of the instant invention is found in a structural arrangement whereby speed acceleration imparted to a given actuated element is intermittent and variable in a manner which is entirely a matter of unpredictable hazard, and hence the relative progress of the actuated elements may not be determined in advance through any evaluation of the mechanical relationships employed in the mechanism or through any computations predicated upon known mathematical principles.

25 In the illustrated embodiment of the invention an arrangement effective for the simultaneous actuation of four separate, like elements along parallel courses in simulation of a race therebetween is shown as mounted and assembled upon a rigid, skeleton frame 10, of any appropriate specific construction, definitive of an elongated, rectangular field or course adapted to be horizontally disposed, as by means of frame legs engageable with and to upstand from a suitable supporting plane. Fixed in spaced parallelism to and longitudinally of the field or course defined by the frame 10, conveniently by attachment to frame struts transverse to said field or course, a plurality of track bars 11 is mounted, one such bar for each of the elements to be actuated by the mechanism, in a uniformity of length approaching, but slightly less than that of the frame-defined field or course. The bars 11 are identical in an arrangement, such as an upwardly-opening, marginal channel extending the full length of each bar, for the guided reciprocation of a slide block 12, to which the toy figures employed may be removably and interchangeably clipped, and for the slidable reception of one side of an endless cord loop 13 engaged with and to effect the translation of said block.

Each cord loop 13 is correspondingly longer than its associated track bar 11 and engages at the forward, or driving, end of the assembly with 55 and about a grooved pulley 14 spacedly aligned

with the adjacent end of the track bar in a freely-rotatable mounting on a shaft 15 journaled on and transversely of the frame 10 and at the rearward end of the assembly each said cord loop engages with and about a similar grooved pulley 16 carried by and for rotation in the free end of a head block 17 slidably associated with the corresponding end of the track bar, thereby to dispose each of said loops 13 for travel between and about its supporting pulleys 14 and 16 with its upper reach or run slidably accommodated in the upper margin channel of the associated track bar 11 and for translation of its attached slide block 12 in and along said channel.

The shaft 15 operates through the pulleys 14, as will hereinafter appear, to drive the cords 13 along their respective track bars and it is the function of each head block 17 to normally tension its cord loop for effective driven reaction to rotation of the mounting pulley 14, for which purpose the inner end of the head block may be forked to embrace the adjacent end of its track bar 11, pins 18 may bridge the head block fork through an elongated slot longitudinally intersecting the track bar, thereby to support said head block on and for extension and retraction relative to the track bar, and a retractile spring 19 may be engaged between appropriate points of the head block and track bar to urge the former into an extension outwardly from the latter and to a consequent tensioning of the cord loop engaged about the pulley 16 carried by the head block. The cord tensioning arrangement just described may be availed of to slacken the cord loop bights between the pulleys 14 and 16 and thereby accommodate manual, or other, adjustment of the slide blocks 12 along their track bars, it being feasible to selectively and simultaneously retract all of the head blocks 17 relative to their supporting track bars 11 and thereby nullify the driving friction of the pulleys 14 relative to the cord loops 13 to an extent permitting the cords to slip freely about said pulleys. To effect such selective retraction of the head blocks 17, a rock shaft 20 is journaled in members of the frame 10 transversely of the frame rearward end beneath the corresponding ends of the track bars 11 and is equipped with a handle 21 whereby it may be oscillated in its mounting, ends of one of the pins 18 connecting each head block to its track bar being extended to project perpendicularly from and at each side of the associated head block, and fingers 22 being fixed in and projecting radially from the rock shaft 20 in position to engage behind such pin 18 end extensions when the handle 21 is rocked forwardly and thereby shift the head blocks in their slide mountings and against the pressure of the tensioning springs 19.

As above noted, the pulleys 14 are freely rotatable on their mounting shaft 15 but they are held in alignment with their respective track bars 11 and against displacement axially along said shaft by suitable means, such as pins or collars 23, and rotation of said shaft 15 in a direction to advance the slide blocks 12 from the rearward end to the forward ends of the track bars 11 is positively transmitted to effect corresponding rotation of all of the pulleys 14 through a spring-loaded detent 24 carried by each pulley 14 in co-action with a ratchet gear 25 fixed to the shaft 15, thus to assure simultaneous and synchronous rotation of the shaft 15 and pulleys 14 in an operative drive direction while accommodating overrun, or higher speed rotation, of said pulleys 14 on and relative to the shaft 15.

A shaft 26 is journaled for rotation on the frame 10 in spaced parallelism with the shaft 15 and corresponding ends of said shafts 15 and 26 exterior to the frame mount like pulleys 27 in coplanar relation with the drive pulley 28 of a gear reducer, or transmission, 29 powered by an electric motor 30, so that a belt 31 operatively connecting the two pulleys 27 with the drive pulley 28 is effective to simultaneously and synchronously rotate said shafts 15 and 26 in the same direction and at a slow speed determined by the unit 29 whenever the motor 30 is energized, thus to drive the pulleys 14 and uniformly advance the slide blocks 12 along their track bars. The actuation thus applied to the separate slide blocks and associated toy elements of the assembly through the arrangement of means so far described is simultaneous and uniform, and it is the function of the means and connections hereinafter set forth to intermittently vary the uniform actuation of the separate block and toy elements in a manner which will preclude advance determination of the relative progress thereof.

For the purpose just set forth, each of the pulleys 14 is furnished with a concentric, fixedly-associated, chain sprocket 32, all of which are alike, and an annularly-grooved drum 33, of a diameter exceeding that of the sprocket 32, is fixed to the shaft 26 for operative association with each said sprocket 32 and hence with its annular groove coplanar with the coacting sprocket. A ladder chain 34, or the equivalent, is engaged as an endless loop with each sprocket 32 and loosely about the aligned drum 33, engaging within the annular groove of the latter, so that as the shafts 15 and 26 are synchronously and simultaneously driven, as above set forth, the chain 34 is steadily and uniformly advanced by each sprocket 32 and slips relative to the periphery of the associated drum 33. However, the face of the drum 33 annular groove engaged by the chain 34 is intersected by a succession of apertures 35 of a size to accommodate the stems of headed pins 36 loosely charged in suitable quantity within the hollow drum interior and hence effective, at hazard as to number and occasion, to traverse and protrude through one or another of the apertures 35 as a tooth or teeth temporarily intercoupling the drum 33 and chain 34 and applying power rotation of said drum, through the relatively greater drum diameter, to increase the speed of rotation of the associated sprocket 32 and the pulley 14 fixed thereto, thus imparting a spurt of speed to the slide block and toy element under advance through the agency of the cord loop 13 driven by said pulley 14. The pins 36 engaging through the holes 35 with links of the chain 34 will maintain a driving connection between a drum 33 and its associated chain only so long as the chain continues to conform to the contour of the drum and maintains a pressure against the projecting pin stem sufficient to hold the latter against the influence of gravity tending to return the pin to the lower portion of the drum interior as the drum is rotated to carry the projecting pin upwardly into position for gravity release from its engagement through the hole 35, it being obvious that as the chain becomes tangent to the drum its links move outwardly relative to the projecting pin stem and soon release the pin to fall back within the drum interior. Each drum normally contains the same number of identical pins 36, though the number of such identical pins in a given drum may be varied as desired. The probability of a pin engaging to interconnect a given

drum 33 with its chain 34 varies somewhat according to the number of identical pins 36 within the drum. The specific shape of the pins 36, the size and number of the holes 35, and the size relationship between the holes 35 and pin stems may all be varied to increase or decrease the probability of driving engagement between a drum 33 and its chain 34, but actual use of the apparatus has demonstrated that with the same number of identical pins 36 in each of a plurality of like drums 33 it is entirely a matter of chance and unpredictable hazard as to how continuously, with what frequency, and in what order the pins 36 will adjust themselves to establish driving connection between their respective drums and associated chains.

In practical operation, the apparatus functions when the motor 30 is energized to continuously, simultaneously, and uniformly advance the slide blocks 12 and associated toy elements to which the cords 13 are attached along the track bars 11, and to intermittently accelerate the advance of certain of said slide blocks and toy elements as driving connection is established by the pins 36 between a drum 33 and chain 34 associated with the corresponding sprocket 32 and pulley 14. Through relatively simple and obvious modifications, the apparatus may conveniently be adapted for intermittently-variable actuation of elements continuously through closed circuits or orbits, the specific form and arrangement of the actuatable elements being, per se, no part of the instant invention.

Since many changes, variations, and modifications in the specific form, construction, and arrangement of the elements shown and described may be had without departing from the spirit of my invention, I wish to be understood as being limited solely by the scope of the appended claim, rather than by any details of the illustrative 40 showing and foregoing description.

I claim as my invention:

In an intermittently-variable drive mechanism having a powered shaft, like drive members spaced apart along and independently rotatable on said shaft, and ratchet and detent means similarly interengaging said drive members and shaft for simultaneous, synchronous rotation in one direction, means directly effective in reaction to shaft drive to intermittently and unpredictably accelerate the rotation of individual drive members on and about their mounting shaft, said latter means comprising a second shaft spacedly paralleling and in synchronously-driven relation with said first shaft, a chain sprocket concentrically and fixedly associated with each said shaft-mounted drive member, a drum of greater diameter than such sprocket fixed to and for rotation with said second shaft in operative alignment with each said sprocket, an annular groove peripherally of the drum, an endless chain engaging each sprocket and embracing the associated drum in sliding accommodation within the groove thereof, holes intersecting the floor of the drum groove, and a plurality of headed pins loosely within the drum for haphazard protrusion of their stems through said holes and into temporary latching engagement with the chain links.
